United States Patent

Des. 242,099
Patented Nov. 2, 1976

242,099

ROOM PARTITION OR SIMILAR ARTICLE

Neil W. Casey, Cupertino, Calif., assignor to The Jack Dymond Company, Mountain View, Calif.

Filed Aug. 13, 1975, Ser. No. 604,460

Term of patent 14 years

Int. Cl. D6—06

U.S. Cl. D6—139

FIG. 1

FIG. 2

FIG. 3

FIG. 4

FIG. 5

FIG. 1 is a top perspective view of a room partition or similar article, showing my new design;

FIG. 2 is a front elevational view thereof;

FIG. 3 is a side elevational view as seen from the right of FIG. 2, the opposite side being substantially a mirror image thereof;

FIG. 4 is a top plan view thereof; and

FIG. 5 is a bottom plan view thereof.

The rear of the room partition is identical to the front.

I claim:

The ornamental design for a room partition or similar article, as shown and described.
